SPECIFICATION forming part of Letters Patent No. 399,836, dated March 19, 1889.

Application filed October 10, 1887. Renewed January 28, 1889. Serial No. 297,830. (No specimens.)

To all whom it may concern:

Be it known that I, PRESLEY S. CHESHIER, a citizen of the United States, and a resident of Excelsior Springs, in the county of Clay and 5 State of Missouri, have invented certain new and useful Improvements in Catarrh Remedies; and I do hereby declare that the following is a full, clear, and exact description of the invention, which will enable others skilled 10 in the art to which it appertains to make and use the same.

My invention consists in a medical compound for the treatment of catarrh of the nose, head, throat, lungs, and stomach, and which 15 will be hereinafter described and claimed.

My medical compound consists of the following ingredients combined in the proportions stated, viz: rain-water, one gallon; sulphate of zinc, four ounces; nitrate potassa, four ounces, 20 and juice of elderberries, four ounces. The last three ingredients having been added to the rain-water in the proportions above given, the whole is shaken until well mixed, and is then let stand for forty minutes, after which it is 25 strained and bottled, when it is ready for use.

This medical compound when prepared in substantially the proportions and in the manner above stated will form a perfect and reliable treatment for catarrh of the nose, head, 30 throat, lungs, and stomach. It is to be used internally and externally, as the nature of each case may demand, being adapted both for internal and topical use to meet the circumstances of all cases of catarrh.

The manner of using is as follows: When 35 suffering from catarrh of the nose and head, the remedy is applied and inhaled from cotton swab until the affected parts are completely saturated, while for catarrh of the throat, lungs, and the stomach fifteen or 40 twenty drops are taken immediately before retiring for the night until cured. The juice of elderberries is full strength, just as it comes from the berries, and is only used for giving color to the compound. 45

I do not claim the use of elderberries and saltpeter, broadly; but claim and desire to secure by Letters Patent of the United States—

A medical compound for the treatment of catarrh, consisting of rain-water, sulphate of 50 zinc, nitrate potassa, and juice of elderberries, in substantially the proportions specified.

In testimony that I claim the foregoing as my own I have hereunto affixed my signature in presence of two witnesses.

PRESLEY S. CHESHIER.
